REEDS.

RUG.

No 17,174.

Patented Mar. 8, 1887.

UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 17,174, dated March 8, 1887.

Application filed January 10, 1887. Serial No. 223,984. Term of patent 3½ years.

To all whom it may concern:

Be it known that I, ADOLPH PETZOLD, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in a center panel ornamented, as shown, by conventional figures after the Persian order of ornamentation, comprising floral masses and geometric boundaries. The whole is surrounded by a wide border, which border consists of a center ornamented by branches, leaves, and flowers, and an inner and outer molding, as shown.

What I claim as my invention is—

The design for a rug, consisting of a center panel ornamented by Persian ornamental figures, as shown, comprising floral masses and geometric boundaries, and an ornamental border of floral figures, as shown.

ADOLPH PETZOLD.
